UNITED STATES PATENT OFFICE

91,783

DESIGN FOR A CANDLESTICK OR ARTICLE OF ANALOGOUS NATURE

Donald G. Macdonald, near Richmond, Va.

Application February 10, 1933, Serial No. 47,172

Term of patent 14 years

To whom it may concern:

Be it known that I, DONALD G. MACDONALD, a citizen of the United States residing near Richmond, in the county of Chesterfield and Commonwealth of Virginia, have invented a new, original, and ornamental Design for Candlesticks or Articles of Analogous Nature, of which the following is a specification, reference being had to the accompanying drawing, forming a part thereof.

The figure is a side elevation of a candlestick embodying my new design. The dominant feature of the design consists in the contour of the lower portion of the candlestick. It is contemplated that the new design may be incorporated in lamp stands, bowls, vases, and supports for other articles.

I claim:

The ornamental design for a candlestick or article of analogous nature as shown and described.

DONALD G. MACDONALD.
